LOCOMOTIVE STOKING MECHANISM

Filed Sept. 7, 1927

INVENTOR,
David T. Williams,
John D. Williams,
ATTORNEY.

UNITED STATES PATENT OFFICE.

DAVID T. WILLIAMS, OF NEW YORK, N. Y.

LOCOMOTIVE-STOKING MECHANISM.

Application filed September 7, 1927. Serial No. 217,965.

In mechanical stokers, and especially those used for delivering to the fire "run-of-mine" or other irregularly-sized fuel, it has been proposed to provide beside the course in which the fuel is advanced by the propelling means of the stoker an abutment which coacts with such means to reduce fuel fragments exceeding a given size to or below that size. Frequently there come mixed with the fuel various foreign bodies, such as metal hooks, chains, fragments of mine-car wheels, coal-picks and other mine paraphernalia, which cannot thus be reduced in the stoker and which consequently cause a jam. When such a jam occurs the fireman (who may quite naturally assume it is due to an unusually refractory lump of coal) is likely to resort to force to break the jam, as by reversing the engine which drives the propelling means and then causing it to drive forward again, usually applying excessive force in this way and repeating the operation a number of times. In consequence, it frequently happens that the strain imposed results in breakage or bending of some part of the stoker mechanism, thus crippling the stoker if not rendering it wholly inoperative. This of course is the result of the sudden shock imposed when the propelling means, as stated being usually at such times driven forward under excessive force, meets with the quite positive resistance opposed by the abutment and intervening non-yielding foreign body.

The object of this invention is to make provision whereby the stoker will absorb the shock gradually and injury thereto will be thus avoided. To this end I resort to elastic means to support one of the elements afforded by the propelling means and abutment against the force opposed thereto by the other, in the example herein shown and described, and as preferred, applying such elastic means to the abutment.

In the accompanying drawing,

Fig. 1 is a longitudinal sectional view of sufficient of a mechanical locomotive stoker embodying the invention to illustrate the latter;

Fig. 2 is a sectional view on line 2—2, Fig. 1; and

Fig. 3 is a plan of the abutment element.

A supporting structure for the propelling and abutment element is in the illustrated example afforded by the tender 1 of a loco-

motive, and suitably supported therein is the rear section 2 of a conduit of which another (and tubular) section is shown at 3, reaching forward to the locomotive 4 and 60 having a universal-joint connection 5 with the section 2; the section 2 is mainly open at the top, or trough-shaped, so as to receive the superjacent fuel in the bunker (not shown) of the tender, but at its forward or 65 joint end portion 2^a it is cross-sectionally continuous and contains an annular member 6 which at 7 affords a bearing. In the instant construction the joint-portion 2^a of the section 2 is separated from the remainder 70 thereof by a vertical wall 1^a of the tender.

The propelling element is here a screw which is revoluble in the conduit, being journaled in part in bearing 7, and is formed of rear and forward sections 8 and 9 having a universal-joint connection 10 between them, the rear section 8 being contained in conduit section 2 and the forward section 9 in conduit section 3. Any means to rotate this screw, such as a steam engine (not 80 shown) according to the usual practice, may be employed. The arrow in Fig. 1 indicates the direction in which the screw normally (that is, forwardly) propels the fuel.

The abutment element, as usual, is placed 85 at that point in the length of the conduit where as soon as practicable in the forward progress of the fuel it will serve, in coaction with the propelling element, to reduce the unduly large fuel pieces to the proper 90 size—in the example, immediately back of the part of the conduit containing the annular member 6, which is the first point in such example where fuel fragments not so reduced would be troublesome. In the present case 95 said abutment element is a hood 11 sloping upwardly and rearwardly, over the screw, and having its underneath face curved transversely of the screw; it is mounted on a plate 12 (here fixed to wall 1^a) so as to be movable 100 up and down, as by being pivoted at its forward end on a transverse pivot 13, and it normally rests with a face 12^a thereof in contact with the wall 1^a of the tender. On its working (here its underneath) face it has 105 rearwardly projecting sharp studs 14 which assist in the reduction of the fuel fragments encountered thereby. At each side suitably rearward of its pivot or fulcrum it has bosses 12^b, and in coincidence with these bosses and 110 on the outer surfaces of the (converging) sides of the conduit section 2 are other bosses

2^b. Each two bosses 12^b and 2^b, together with the corresponding side of conduit section 2, have passing freely through them a long bolts 15 whose head seats on the boss 5 12^b; and on this bolt is a spring 16 which seats against the boss 2^b; a disk 17 seated against the lower end of such spring, and nuts 18 screwed on the bolt and taking against the disk.

10 Thus the abutment, movable as described, is movable from its normal position (resting with its surface 12^a in contact with wall 1^a) subject to elastic resistance. Adjustment may be effected by manipulating 15 the nuts 18, to attain that degree of such resistance which is needed in the reducing of such fuel lumps, and if any foreign body is encountered which is more refractory than are the fragments of the fuel being 20 handled the incidental shock will not be sudden and hence violent but will be gradual and hence absorbed and undue strain on the stoker will be avoided. A factor in the absorbence of the shock is the fact that 25 the yielding is transversely of and hence away from the course in which the fuel is propelled; in fact, the convergence of the under or fuel-contact surface of the abutment with respect to said course is also it- 30 self, in a measure, such a factor.

I claim:

1. In a mechanical stoker, the combination of a supporting structure, means there- 35 in to convey the fuel in a definite course in- cluding a fuel-propelling element, and an abutment element normally beside said course, said elements being normally held in given positions to coact with each other to exert reducing pressure on the fuel but one 40 of them being yieldable out of its said position.

2. In a mechanical stoker, the combination of a supporting structure, means there- 45 in to convey the fuel in a definite course in- cluding a fuel-propelling element, and an abutment element normally beside said course, said elements being in given positions to coact with each other to exert re- 50 ducing pressure on the fuel but one of them being yieldable out of its said position and elastically held against such yielding.

3. In a mechanical stoker, the combination of a supporting structure, means there- 55 in to convey the fuel in a definite course in- cluding a fuel-propelling element, and an abutment element beside said course, said ele- 60 ments being normally held in given positions to coact with each other to exert reducing pressure on the fuel but one of them being yieldable out of its said position and trans- versely of said course.

4. In a mechanical stoker, the combination of a supporting structure, means there- 65 in to convey the fuel in a definite course in- cluding a fuel-propelling element, and an

abutment normally beside said course nor- mally held in a given position to coact with the propelling element to exert reducing pressure on the fuel but yieldable out of its 70 said position.

5. In a mechanical stoker, the combina- 75 tion of a supporting structure, means there- in to convey the fuel in a definite course including a fuel-propelling element, and an abutment normally beside said course in a given position to coact with the propelling element to exert reducing pressure on the fuel but yieldable out of its said position and elastically held against such yielding.

6. In a mechanical stoker, the combina- 80 tion of a supporting structure, means there- in to convey the fuel in a definite course including a fuel-propelling element, and an abutment beside said course normally held in a given position to coact with the prop- 85 pelling element to exert reducing pressure on the fuel but yieldable out of its said position and transversely of said course.

7. In a mechanical stoker, the combina- 90 tion of a supporting structure, means there- in to convey the fuel in a definite course including a fuel-propelling element, and an abutment beside said course normally held in a given position to coact with the propel- 95 ling element to exert reducing pressure on the fuel but yieldable out of its said position pivotally on a relatively forward axis extending transversely of said course.

8. In a mechanical stoker, the combina- 100 tion of a supporting structure, means there- in to convey the fuel in a definite course in- cluding a fuel-propelling element, and an abutment beside said course normally held in a given position to coact with the propel- 105 ling element to exert reducing pressure on the fuel but yieldable out of its said position and having a fuel-contact surface con- verging toward said course.

9. In a mechanical stoker, the combina- 110 tion of a supporting structure, means there- in to convey the fuel in a definite course in- cluding a fuel-propelling element, and an abutment element beside said course, said ele- 115 ments being normally held in given positions to coact with each other to exert re- ducing pressure on the fuel but one of them being yieldable out of its said position.

10. In a mechanical stoker, the combina- 120 tion of a supporting structure, means there- in to convey the fuel in a definite course in- cluding a fuel-propelling element, and an abutment element beside said course, said ele- 125 ments being in given positions to coact with each other to exert reducing pressure on the fuel but one of them being yieldable out of its said position and elastically held against such yielding.

11. In a mechanical stoker, the combina- 130 tion of a supporting structure, means there- in to convey the fuel in a definite course in-

cluding a fuel-propelling element, and an abutment beside said course normally held in a given position to coact with the propelling element to exert reducing pressure on the fuel but yieldable out of its said position.

12. In a mechanical stoker, the combination of a supporting structure, means therein to convey the fuel in a definite course including a fuel-propelling element, and an abutment beside said course in a given position to coact with the propelling element to exert reducing pressure on the fuel but yieldable out of its said position and elastically held against such yielding.

13. In a mechanical stoker, the combination of a supporting structure, means therein to convey the fuel in a definite course in-

cluding a fuel-propelling element, and a fuel-abutment element, said elements being normally held in positions to coact with each other to exert reducing pressure on the fuel but one of them being yieldable out of its said position transversely of said course.

14. In a mechanical stoker, the combination of a supporting structure, means therein to convey the fuel in a definite course including a fuel-propelling element, and a fuel-abutment element normally held in position to coact with the propelling element to exert reducing pressure on the fuel but yieldable out of said position transversely of said course.

In testimony whereof I affix my signature.

DAVID T. WILLIAMS.
